UNITED STATES PATENT OFFICE.

LEON M. MOLLOY, OF WEST HAVEN, CONNECTICUT, ASSIGNOR TO THE JAMES F. MOLLOY CO., OF NEW HAVEN, CONNECTICUT, A CORPORATION.

BUCKLE.

1,282,704.

Specification of Letters Patent.

Patented Oct. 22, 1918.

Application filed April 20, 1917. Serial No. 163,387.

To all whom it may concern:

Be it known that I, LEON M. MOLLOY, a citizen of the United States, residing at West Haven, in the county of New Haven and State of Connecticut, have invented a new and useful Improvement in Buckles; and I do hereby declare the following, when taken in connection with the accompanying drawings and the characters of reference marked thereon, to be a full, clear, and exact description of the same, and which said drawings constitute part of this application, and represent, in—

Figure 1 a face view of a buckle constructed in accordance with my invention and shown as applied to a suspender web.

Fig. 2 a sectional view of the same.

Fig. 3 a plan view of the buckle, detached.

20 This invention relates to an improvement in buckles, and while adapted for use as a buckle for use on suspenders or hose supporters, is adapted for various other purposes. The invention particularly relates 25 to one-piece buckles of the so called slide type.

The object of the invention is to so form the buckle and so fix the web that the webbing will be firmly held and an ornamental plate provided for the buckle; and the invention consists in the construction hereinafter described and particularly recited in the claim.

In carrying out my invention I employ a 35 flat plate 4 formed with transverse slots 5, 6, forming a top bar 7 and a bottom bar 8, and a so called face-plate 9, the terms "top" and "bottom" being used relatively. The bottom bar 8 as shown, is slightly offset and the 40 edge 10 turned outward so as to form a gripping edge for the purpose as will hereinafter appear. This buckle is used in con-

nection with a web 11 which passes through the slot 5 over the bar 7 beneath the face-plate 9, outward through the slot 6 over the 45 bar 8, downward and through a loop or other device 12, the end 13 being folded over the top bar 7 and secured thereto. The strain upon the loop 12 or other device imposes a drawing action upon the top of the 50 buckle which tends to cause it to tip so as to throw the bottom bar outward, thus causing the buckle to take a firm grip upon the strap the edge 10 of the bar 8 assisting in preventing the strap from slipping particularly when a heavy web is used. In this construction the back of the buckle is completely covered by the strap so that a rustless buckle is produced, and the face-plate 9 or central portion of the buckle is not 55 covered, permitting that face-plate to be ornamented or engraved, as desired, thus giving a very pleasing appearance to a buckle of the type herein referred to.

I claim:—

65 A slide buckle formed from a single piece of metal having transverse slots near its upper and lower edges forming top and bottom bars and a central ornamental face plate between them, combined with a web 70 one end of which is secured to said top bar, the web extending downward, thence upward over the bottom bar under the face plate and over the top bar, a portion of the web secured thereto whereby said ornamental plate is presented to view.

In testimony whereof I have signed this specification in the presence of two subscribing witnesses.

LEON M. MOLLOY.

Witnesses:

CATHERINE E. MORAN,
JOSEPH COOPEY.
